CLAIM

The ornamental design for a combined electric ceiling fan and light, as shown and described.

DESCRIPTION

FIG. 1 is a perspective view of a combined electric ceiling fan and light, showing my new design;

FIG. 2 is an enlarged top plan view thereof;

FIG. 3 is an enlarged bottom plan view thereof; and,
FIG. 4 is an enlarged side elevation view thereof, the opposite side being identical to that shown.

The rear of the design is identical to the front as shown in FIG. 1.

The blades have been shown broken-away in FIGS. 2-4 for ease of illustration.

FIG. 1

FIG. 2

FIG. 3

FIG. 4
